Primary Examiner — Selina Sikder(74) *Attorney, Agent, or Firm* — Panitch Schwarze Belisario & Nadel LLP(57) **CLAIM**

The ornamental design for a compressor control with stand, as shown and described.

DESCRIPTION

FIG. 1 is a front perspective view of a compressor control with stand in accordance with a preferred embodiment of my new design;

FIG. 2 is a left side perspective view thereof;

FIG. 3 is left side elevational view thereof, a right side elevational view being a mirror image thereof;

FIG. 4 is a rear perspective view thereof; and,

FIG. 5 is a top perspective view thereof.

The bottom view of the compressor control is not shown in the drawings or described in the specification and, therefore, forms no part of the claimed design.
